UNITED STATES PATENT OFFICE.

CHARLES BOOZE, OF BUFFALO, NEW YORK, ASSIGNOR TO M. H. BIRGE & SONS, OF SAME PLACE.

DESIGN FOR WALL-PAPER.

SPECIFICATION forming part of Design No. 22,899, dated November 14, 1893.

Application filed October 7, 1893. Serial No. 487,520. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification.

The design consists of a series of ornamental figures formed of scrolls, flowers and leaves 10 as represented in the accompanying drawing. The ornamental figures are placed at regular distances apart over the surface of the paper. The border or upper portion of the design is 15 formed of the same ornamental figures with branches of leaves extended, forming scrolls which connect with ornamental figures at the sides of said ornaments and forming a continuous border.

What I claim is—

1. The design for wall paper herein shown 20 and described.
2. In the design for wall paper the border herein shown and described.

Witness my hand this 2d day of October, 1893.

CHARLES BOOZE.
